INVENTOR.

Wm. J. Merritt.

UNITED STATES PATENT OFFICE.

WILLIAM J. MERRITT, OF BARDOLPH, ILLINOIS.

IMPROVEMENT IN FLOUR-BOLTS.

Specification forming part of Letters Patent No. 171,525, dated December 28, 1875; application filed May 31, 1875.

To all whom it may concern:

Be it known that I, WILLIAM J. MERRITT, of Bardolph, in the county of McDonough and State of Illinois, have invented a new and useful Improvement in Flour-Purifiers; and I do hereby declare that the following is a full, clear, and exact description of the same, which will enable others skilled in the art to make and use the same, reference being had to the accompanying drawing forming a part of this specification.

My invention consists in the construction of suitable machinery for both purifying and cooling at the same time the flour before it is introduced into the bolt; and its novelty consists in arranging a cylinder above the bolting-chest, provided with an exhaust air-blast, as hereinafter described.

In the drawing, A A represent the frame of the bolting-chest, on top of which is placed the cylinder H, which consists of a center shaft fitted into suitable frame-work at each end. This shaft has cross-arms, to which the ribs I I are attached. At the left these ribs angle inwardly to the shaft. The covering is made of heavy canvas and oiled. The angles a a are open. B B represent the bolts in the chest. D represents the line-shaft, which gives motion to the bolts B B and cylinder H by means of the bevel-wheels s s s. E represents the fan-blower shaft, to which the fans J J are attached. C represents the suction-pipe leading from the cylinder H to the fan-blower.

The operation is as follows: The unbolted flour is elevated and introduced into the cylinder H at the spout d. Motion is applied to the shaft D, which gives motion to the bolts B B and cylinder H, and motion is also applied to the fan-blower. As soon as the cylinder H commences to revolve it commences to agitate the flour by raising it up the sides, and pouring it down again, which is done by

means of the ribs I I, which extend inwardly for that purpose. The agitation of the flour in the cylinder sets free all the light and fine particles of bran and other impurities. The suction force from the fan-blower draws a current of air through the cylinder by means of and through the pipe C, indicated by the arrows, which both cools the flour and catches all these impurities as fast as set free, which are sucked into and pass through the pipe C into the fan, which forces it out into the lower bolt, and then it goes into the second grade of flour. The end of the pipe that returns from the fan to the lower bolt turns down to check the current of air which prevents any agitation in the bolt. The cylinder H is inclined to the left, which causes the flour, by means of gravitation to run that way, and as fast as it runs out of the cylinder it passes out into the spout r, and down into the upper bolt cooled and thoroughly cleansed of all the impurities that would otherwise go into the fine flour.

I am aware that devices have been constructed and used for cleansing middlings by means of an air-blast, and also that flour has been subjected to currents of air for the purpose of cooling it; but I am not aware that flour has been both cooled and purified at the same time before being introduced into the bolt, as set forth in the foregoing specification.

Having thus fully described my invention, what I claim as new, and desire to secure by Letters Patent, is—

The combination of inclined superposed cylinder H, and pipe C, with the first and second grade bolts B B, and the exhaust-fan, substantially as described, and for the purpose set forth.

WM. J. MERRITT.
